COMBINED BAR CABINET AND REFRIGERATOR

Leif Elvestad, Skogfaret 17C, Haslum, Norway

Filed Oct. 20, 1969, Ser. No. 19,642

Term of patent 14 years

Int. Cl. D6—04

U.S. Cl. D33—19

FIG. 2

FIG. 1 is a perspective view of the combined bar cabinet and refrigerator with the doors and the top closure in closed position.

FIG. 2 is a front perspective view of the design for a combined bar cabinet and refrigerator with the doors and the top closure in open position and with the back thereof being conventional.

I claim:

The ornamental design for a combined bar cabinet and refrigerator, as shown and described.
